US00D752751S

(12) **United States Design Patent**
Radzinsky

(10) **Patent No.:** **US D752,751 S**
(45) **Date of Patent:** **** Mar. 29, 2016**

(54) **PROSTHETIC ADAPTOR**

(71) Applicant: **Vladimir Radzinsky**, Torrance, CA
(US)

(72) Inventor: **Vladimir Radzinsky**, Torrance, CA
(US)

(**) Term: **14 Years**

(21) Appl. No.: **29/517,933**

(22) Filed: **Feb. 18, 2015**

Related U.S. Application Data

(60) Division of application No. 14/204,591, filed on Mar. 11, 2014, which is a continuation-in-part of application No. 14/162,087, filed on Jan. 23, 2014.

(57) **CLAIM**

The ornamental design for a prosthetic adaptor, as shown and described.

DESCRIPTION

FIG. 1 is a perspective view of the prosthetic adaptor;
FIG. 2 is a top plan view of the prosthetic adaptor;
FIG. 3 is a front elevation view of the prosthetic adaptor;
FIG. 4 is a rear elevation view of the prosthetic adaptor;
FIG. 5 is a left elevation view of the prosthetic adaptor;
FIG. 6 is a right elevation view of the prosthetic adaptor; and,
FIG. 7 is a bottom plan view of the prosthetic adaptor taken along lines 2-7 of FIG. 3.

The broken line showing is included for the purpose of illustrating environment and forms no part of the claimed design.

1 Claim, 3 Drawing Sheets
